JOHN L. DRAKE, OF TOLEDO, OHIO, ASSIGNOR TO LIBBEY-OWENS-FORD GLASS COMPANY,
OF TOLEDO, OHIO, A CORPORATION OF OHIO

CAR OR TABLE TRANSFER MEANS

Application filed June 27, 1929. Serial No. 374,028.

This invention relates to the grinding and polishing of sheet or plate glass or other flat sheets or plates to be surfaced and more especially to an apparatus for this purpose of the so-called continuous type.

Various systems for the continuous grinding and polishing of plate glass have heretofore been proposed and in practically all of such systems there have been provided a series of cars or tables mounted upon wheels and adapted to be rolled along tracks in a continuous train first under a series of grinding units and then under a series of polishing units.

In the particular arrangement to which this invention is applied, three parallel tracks are employed, the two outside tracks being working tracks passing beneath a series of grinding and polishing runners and the single central track constituting the return track for bringing the cars or tables back to their starting position on the working tracks.

The primary object of the present invention is the provision of improved means for facilitating the handling of the cars or tables and more particularly for effecting the transfer of said tables from the working tracks to the return track or vice versa in a rapid and efficient manner.

Another object of the invention is the provision of novel transfer means of the above character including a plurality of transfer tables at one or both ends of the parallel tracks, each transfer table being movable into operative relation with the central track and with one of the outside tracks.

Other objects and advantages of the invention will become more apparent during the course of the following description when taken in connection with the accompanying drawing.

The drawing represents diagrammatically a top plan view of transfer apparatus provided by the present invention.

Referring to the drawing, three parallel

tracks 5, 6 and 7 are employed, the outside tracks 5 and 6 constituting the working tracks and the single central track 7 constituting the return track of the system. These tracks are adapted to carry a series of work cars or tables 8 upon the upper surfaces of which are secured glass sheets 9 to be ground and polished.

In practice, the glass sheets to be surfaced are secured upon the cars 8 at the right hand end of working tracks 5 and 6 and are carried along these tracks beneath a series of grinding runners (not shown), and then beneath a series of polishing runners 10, the cars being preferably coupled together to form a continuous train. When the cars reach the left hand end of working tracks 5 and 6, the glass sheets are removed therefrom and the said cars are uncoupled, and transferred to the return track 7 along which they are moved to the starting end of the working tracks.

The present invention contemplates the provision of improved transfer means between the tracks 5, 6 and 7 at one or both ends for transferring the cars from the working tracks to the return track or vice versa. This transfer means consists of a pair of rotatable transfer or turn-tables 11 and 12, each table being common to the central return track 7, and adapted to serve one of the outside working tracks 5 or 6 so that cars 8 may be alternately received from the working tracks 5 and 6 and transferred to return track 7.

Each of the transfer tables 11 and 12 is of elongated formation and is provided with the curved or arcuate outer ends 13 and 14 while the sides thereof are cut away or recessed as at 15 and 16, said recesses having the same curvature as the ends 13 and 14. Thus, the sides and ends of the transfer table are oppositely curved and the reason for such a construction will be more clearly hereinafter apparent. Each transfer table 11 and 12 carries adjacent the opposite ends thereof the two parallel track sections 17 and 18, said table

being intermittently rotated by means of a motor 19 driving a pinion 20 meshing with ring gear 21 carried by said table. Each transfer table may also be supported upon a plurality of wheels 22 running upon an annular trackway 23.

The transfer tables 11 and 12 are so mounted that they are adapted to interengage one another and rotate in overlapping paths.

- 10 When the tables are interengaged, one of said tables will be in operative position with respect to the return track 7 and its corresponding working track, while the other table will be in an inoperative position with respect to 15 both of its tracks. In other words, the transfer table in operative position will extend transversely of said tracks while the other transfer table will extend longitudinally thereof and at right angles to the first table, 20 one end of the transfer table in operative position being received within the recess in the adjacent side of the other transfer table.

In carrying the invention into practice, the transfer table 11 is adapted to receive the 25 cars 8 from working track 5 and to deliver them onto the return track 7, while the transfer table 12 is provided to receive the cars from working track 6 and deliver them onto return track 7. During the operation of one 30 transfer table, the other table is idle so that said tables are intermittently operated to receive cars alternately from the working tracks 5 and 6 and deliver them to return track 7. For instance, when the transfer table 35 12 is in the position indicated in the drawing, the track sections 17 and 18 thereof are in registry with tracks 6 and 7 respectively so that a car can be received on said transfer table from working track 6 and a car simultaneously discharged therefrom onto return track 7. When transfer table 12 is in such position, the transfer table 11 will extend at substantially right angles thereto and longitudinally between the tracks 5 and 7, the two 40 tables being interengaged in such a manner that the end 14 of the table 12 is received within the recess 16 in the adjacent side of table 11.

After the car on the track section 18 of the 45 transfer table 12 has been moved onto the return track 7 and another car moved from the working track 6 onto track section 17 of said table, the said transfer table is rotated a quarter of a revolution in the direction indicated by the arrow in the drawing and stopped, after which the transfer table 11 is rotated in the opposite direction to bring the track sections 17 and 18 thereof into alignment with the tracks 5 and 6 respectively so as 50 to discharge a car onto the return track and receive a car from the working track. The above cycle of operations is then repeated so that the relative positions of the transfer tables 11 and 12 is alternately reversed so as 55 to transfer a car first from one working track

to the return track and then from the other working track to said return track.

It is to be understood that the form of the invention herewith shown and described is to be taken as the preferred embodiment of the 70 same, and that various changes in the shape, size and arrangement of parts may be resorted to without departing from the spirit of the invention or the scope of the subjoined claims.

I claim:

1. The combination with a plurality of parallel tracks adapted to carry a series of cars or carriers, of a plurality of rotatable transfer tables provided at one end of said tracks for transferring the cars from one track to an adjacent track, the paths of travel of said transfer tables overlapping one another.

2. The combination with a plurality of parallel tracks adapted to carry a series of cars or carriers, of a plurality of rotatable transfer tables provided at one end of said tracks for transferring the cars from one track to an adjacent track, said transfer tables being movable alternately into operative position with respect to one of said tracks.

3. The combination with a plurality of parallel tracks adapted to carry a series of cars or carriers, of a plurality of rotatable transfer tables provided at one end of said tracks for transferring the cars from one track to an adjacent track, said tables being adapted to interengage one another.

4. The combination with a plurality of parallel tracks adapted to carry a series of cars or carriers, of a plurality of rotatable transfer tables provided at one end of said tracks for transferring the cars from one track to an adjacent track, one of said transfer tables being in operative position with respect to the tracks while the other is in an inoperative position.

5. The combination with a plurality of parallel tracks adapted to carry a series of cars or carriers, of a plurality of rotatable transfer tables provided at one end of said tracks for transferring the cars from one track to an adjacent track, each of said transfer tables extending transversely of the tracks when in operative position and longitudinally thereof when in inoperative position.

6. The combination with three parallel tracks for carrying a series of cars or carriers, of a pair of rotatable transfer tables at one end of said tracks, each of said tables being movable into operative position with respect to the inside track and one outside track.

7. The combination with three parallel tracks for carrying a series of cars or carriers, of a pair of rotatable transfer tables at one end of said tracks, each of said tables being adapted to register with the inside track and one outside track, one of said tables being in operative position while the other table is in

an inoperative position at substantially right angles thereto.

8. The combination with three parallel tracks for carrying a series of cars or carriers, of a pair of elongated rotatable transfer tables at one end of said tracks, each of said tables being adapted to register with the inside track and one outside track, said tables being adapted to interengage one another with their paths of travel overlapping one another.

Signed at Toledo, in the county of Lucas and State of Ohio, this 22nd day of June, 1929.
